END PIECE FOR SLIDE FASTENER CLOSURES

Filed Jan. 8, 1944

UNITED STATES PATENT OFFICE

2,471,461

ENDPIECE FOR SLIDE FASTENER CLOSURES

Albert Süsskind, Lugano-Cassarate, Switzerland

Application January 8, 1944, Serial No. 517,519½
In Germany October 24, 1935

9 Claims. (Cl. 24—205.11)

1

This application is a continuation in part of my copending application Ser. Number 351,816, filed August 8, 1940, now abandoned, which in turn is a continuation of my copending application Ser. Number 106,049, filed October 16, 1936, now abandoned. The application is concerned with "zipper" end pieces as disclosed in said abandoned applications, adapted to be firmly attached to the "zipper" tapes against longitudinal as well as transversal displacement by abutting against "zipper" elements other than the last elements of the "zippers" and particularly by abutting against those parts, i. e. the shanks, of said elements which are immovably held by being clamped to said tapes.

The known end pieces are attached to the "zippers" by being clamped directly upon the fabric tapes which they engage and penetrate more or less by teeth or the like provided on said end pieces.

This requires the use of rather thick and stiff metal for the end pieces and the use of special tools for their attachment.

The invention dispenses with these necessities.

Thus the end pieces are attached to the "zipper" indirectly by means of the firmly attached fastener elements and, therefore, in spite of their thin material, as reliably as the old type end pieces.

In the drawing some embodiments of the object of the invention are shown by way of example.

Fig. 1 is a plan of a flat blank for the production of an end piece for the open end of the "zipper";

Fig. 2 is a similar plan for a modified form of such an end piece;

Fig. 3 is a similar plan of an end piece for the closed end of a "zipper";

Fig. 4A is a side view of a further modification of and substitute for an end piece for the closed end of a "zipper";

Fig. 4B is a perspective of the end piece of Fig. 4A in closed condition, "zipper" omitted;

Fig. 5 is a plan view of a "zipper" with the end pieces of Figs. 1, 2, and 4;

Fig. 6 is a transversal section on the line 6—6 of Fig. 5;

Fig. 7 is a longitudinal section on the line 7—7 of Fig. 5;

Fig. 8 is a longitudinal section on the line 8—8 of Fig. 5;

Fig. 9 is a transversal section on the line 9—9 of Fig. 5.

2

Fig. 11 is a section on the line 11—11 of Fig. 10.

The blank shown in Fig. 1 consists of the two main parts 11 and 12 connected by a bridge 13, thus forming a yoke. The part 11 has a rectangular opening or window 14, and the part 12 a similar opening 15. These openings are confined by the inner edges of webs 16, 17, 18 and 19, 20, 21, respectively, and by the edges 22 and 23, respectively.

One side of the blank is provided with teeth or tongues 24, and the other side with corresponding notches 25.

At the upper end of the blank teeth 26 and 27 are provided.

For producing from this blank the end piece 28 shown in Fig. 5 the blank is folded into U-form along the dot and dash lines 29 and 30.

Before the end piece is completely closed it is put, in the manner shown in Fig. 5, upon one end of the tape 31 provided from end to end with fastener elements 32.

Advantageously at least part of the elements 32 are already in engagement with corresponding elements of a companion tape 34. Preferably first a long compound strip is produced consisting of two individual strips studded with elements from end to end without intermediate spaces, the elements of one of the latter strips engaging between the elements of the other of said strips. From this compound strip pieces of a length corresponding to the desired "zippers" are cut.

Having been put in place the U-shaped end piece is firmly pressed together, yielding not only along the longitudinal dot-and-dash lines 29 and 30, but also along the transversal dot-and-dash lines 221, 222, 223, 224.

Thereby the webs 18 and 21 engage the heads 35 of the elements 32, and the webs 16 and 19 engage behind and abut against the foot surfaces 36 of the elements, overlapping said elements at this point, thereby acting as longitudinal abutments against transversal displacement of the end piece, all as shown in Fig. 6.

The webs 17 and 20 overlap and abut against the back surface 37 of the third element from the top, and the surfaces 22 and 23 overlap and abut against the breast surfaces 38 of the topmost element, whereby all these parts of the end piece act as transversal abutments against longitudinal displacement of the end piece, all as shown in Fig. 7.

The teeth 26 and 27, also bent at right angles, may be used for holding an extension tab 39.

It is to be noted that in the embodiment of the invention just described as well as in all the embodiments to be described later the abutments abut against the element shanks 321 which are securely clamped to the tapes 31, 34, and that the transversal abutments abut against such shanks of elements which are remote from the end of the "zipper." These features are very important for the invention.

By the described overlappings, the end piece, in spite of the thin gauge of its material, is reliably secured on the elements, against accidental disengagement, simultaneously in longitudinal as well as in transversal direction without need for any means of direct connection with the tape.

For all the bending operations mere finger pressure is sufficient.

The blank shown in Fig. 2, for the production of the end piece 40 (Fig. 5), consists of two main parts 41 and 42 connected by a bridge 43.

Extensions 44 and 45 are provided on the lower end of the blank to form transversal abutments, extensions 46 and 47 at the outer edges and extensions 48 and 49 at the inner edges of the blank form longitudinal abutments.

Teeth 240, 260 and 270 and notches 250 are provided similar to Fig. 1 and require no detailed description.

As a preparatory step all the extensions are bent through an angle of 90°, and the blank is bent into U-shape, all as indicated by the dot-and-dash lines 50, 51, 52, 53, 54, 55, respectively, so that a box like structure, somewhat similar to that shown in Fig. 4, is formed.

This structure is pressed home on the tape 34, as shown in Fig. 5; at 40, in which operation it yields somewhat along the dot-and-dash lines 221, 222, which correspond to the lines 221, 222 of Fig. 1.

The described extensions again overlap and abut against the shanks of the elements on so many sides that they in all directions reliably prevent accidental disengagement.

The blank, shown in Fig. 3, consists of two main parts 56, 57, connected by a bridge 58. The part 56 at its free end has a longitudinal short arm or shank 59 with an inwardly projecting tooth 60 and a longitudinal longer arm or shank 61 with an inwardly projecting tooth 62. Correspondingly the part 57 at its free end has a short longitudinal arm or shank 63 with tooth 64 and a longer longitudinal shank or arm 65 with tooth 66. Each arm or shank with its tooth forms what I call an angular hook. The teeth of the hooks, thus, are offset longitudinally relative to one another. The distance between the inner edges 67 and 68 of the arms 59 and 61, on the one hand, and between the inner edges 69 and 70 of the arms 63 and 65, on the other hand, is a trifle larger than the combined width of the interengaging elements 32. Teeth 261 are provided for locking the end piece in folded condition.

For attaching this end piece to the closed end of the "zipper," instead of the end piece 83 of Fig. 5, it is folded in U-form along the dot-and-dash lines 71 and 72.

At the end of the operation the teeth 60, 62, 64, 66, enter into the free gaps between the outward ends of the interengaging elements 32 thereby forming transversal abutments preventing longitudinal displacement of the end piece.

The arms 59, 61, and 63, 65 lie along the foot surfaces 36 and 73 of the interengaging elements 32. The edges 67, 68, 69, 70 abutting against said

foot surfaces and thus forming longitudinal abutments prevent any transversal displacement of the end piece.

Fig. 4A shows in open and Fig. 4B in closed condition an end piece 74 in the form of a flat box consisting of main parts 75, 76, bridge 77, lateral longitudinal flanges 78, 79, 83, 84, forming longitudinal abutments against transversal displacement, and transversal flanges i. e. front flanges 82, 80, 84, 85 forming transversal abutments against longitudinal displacement.

Fig. 5 shows this end piece 74 in applied condition.

The front flanges 82, 80, 84, 85 engage into the gaps between adjacent elements, and the lateral flanges 78, 79, 83, 84 overlap the foot surfaces of the elements so that any displacement is prevented, as shown in detail in Figs. 8 and 9. From Figs. 1, 4 and 8 it is to be seen that the transversal flanges 80, 85, 82, 84 have a distance from the bridge 77 greater than the thickness of two elements. Consequently said flanges engage elements which are sufficiently remote from the end of the "zipper" to secure a firm hold or anchorage.

What I claim is:

1. A "zipper" end piece comprising a substantially U-shaped body of thin sheet material adapted to be attached by mere finger pressure without need for a tool, longitudinal abutments integral with said body adapted to abut against a foot surface of fastener elements of a "zipper" and transversal abutments also integral with said body adapted to abut against a broadside surface of said elements in such a manner as to prevent, by said abutting, longitudinal as well as transversal displacement of the end piece, at least one of said transversal abutments having such a distance from the respective end of the "zipper" as to abut, in applied condition of the end piece, against at least the second element of the "zipper."

2. A "zipper" end piece comprising a substantially U-shaped body of thin sheet material adapted to be bent and attached by mere finger pressure without need for a tool, longitudinal abutments integral with said body, adapted to abut against a foot surface of fastener elements of a "zipper" and transversal abutments also integral with said body, adapted to abut against a broadside surface of said elements in such a manner as to prevent, by said abutting, longitudinal as well as transversal displacement of the end piece, at least one of said transversal abutments extending so close to the plane of one of said longitudinal abutments as to abut against a shank of an element.

3. A "zipper" end piece comprising a substantially U-shaped body of thin sheet material adapted to be bent and attached by mere finger pressure without need for a tool, longitudinal abutments integral with said body adapted to abut against a foot surface of fastener elements of a "zipper" and transversal abutments also integral with said body adapted to abut against a broadside surface of said elements in such a manner as to prevent, by said abutting, longitudinal as well as transversal displacement of the end piece, at least one of said transversal abutments having such a distance from the respective end of the "zipper" as to abut, in applied condition of the end piece, against at least the second element of the "zipper," at least one of said transversal abutments extending so close to the plane of one of said longitudinal abutments as to abut against a shank of an element.

4. An end piece as claimed in claim 3 for the

open end of a "zipper," said transversal abutments being separated by a distance corresponding to the length of one element of the "zipper."

5. An end piece for the closed end of a "zipper," said end piece comprising two connected main parts forming together a substantially U-shaped body of thin sheet metal adapted to be bent and attached by mere finger pressure without need for a tool, longitudinal shanks at the free end of each of said main parts at the outer sides of the latter, an inwardly directed tooth at the end of each of said shanks, the distance between the inner edges of the longitudinal shanks of each main part corresponding to the distance between the foot surfaces of interengaged elements, the distance between the teeth of each pair of shanks corresponding to the length of the overlapping parts of interengaged elements, and one of said longitudinal shanks being longer than the other by an amount corresponding to the thickness of one element, all said main parts, shanks and teeth forming an integral structure.

6. An end piece for the closed end of a "zipper," said end piece comprising two main parts connected by a bridge and longitudinal and transversal flanges all integrally connected to form a flat box bent from a thin sheet of metal adapted to be bent and attached by mere finger pressure without need for a tool, said longitudinal flanges having a distance from one another slightly greater than the distance between the foot surfaces of the interengaged "zipper" elements.

7. An end piece for the closed end of a "zipper," said end piece comprising two main parts connected by a bridge and longitudinal and transversal flanges all integrally connected to form a flat box bent from a thin sheet of metal adapted to be bent and attached by mere finger pressure without need for a tool, said longitudinal flanges

having a distance from one another slightly greater than the distance between the foot surfaces of the interengaged "zipper" elements and at least one of said transversal flanges having from said bridge a distance equal to the added thickness of at least two elements.

8. An end piece for the closed end of a "zipper," said end piece comprising two main parts connected by a bridge and longitudinal and transversal flanges all integrally connected to form a flat box bent from a thin sheet of metal adapted to be bent and attached by mere finger pressure without need for a tool, said longitudinal flanges having a distance from one another slightly greater than the distance between the foot surfaces of the interengaged "zipper" elements, and said transversal flanges having an opening big enough to receive those parts of interengaged elements which overlap one another.

20 9. An end piece for the closed end of a "zipper" having longitudinal abutments, adapted to abut against the foot surfaces of interengaged elements, and transversal abutments offset longitudinally relative to one another.
